WARP SWITCH

Burton E. Shaw, Lawrence, Mass., assignor to
 Penn Electric Switch Co., Goshen, Ind., a cor-
 poration of Iowa

Application September 11, 1944, Serial No. 553,560

2 Claims. (Cl. 200—122)

1

My present invention relates to a warp switch which is so designed that it can be readily assembled as a so-called stack switch or one in which various leaf spring elements of the switch are supported in a stack of insulation spacers.

One object of the invention is to provide a warp switch having stationary and movable contacts and an actuating blade for the movable contacts with a toggle spring connection between the actuating blade and the movable contact.

Another object is to provide means to automatically move the actuating blade comprising a bimetal element adjacent which an electrical heater is positioned, the bimetal element and the heater being supported in the stack of insulation spacers with the bimetal element assisting in the support of the heater.

Still another object is to provide "trip-free" resetting mechanism including a reset button which is slidably mounted in a support that is also supported in the stack of insulation spacers.

A further object is to provide a pair of adjusting means for the switch, particularly for the actuating blade thereof to determine the position of the toggle spring at one limit of its movement, and to engage the switch blade at one point to determine its position during resetting operations, the adjustment means being supported on a blade that is also in turn supported in the insulation spacers.

With these and other objects in view, my invention consists in the construction, arrangement and combination of the various parts of my device whereby the objects contemplated are attained, as hereinafter more fully set forth, pointed out in my claims and illustrated in the accompanying drawings, wherein:

Figure 1 is a side elevation of my warp switch showing the switch in set position.

Figure 2 is an end elevation thereof.

Figure 3 is a view similar to Figure 1 with the switch tripped by warpage of the bimetal element caused by energization of its heater.

Figure 4 is a view similar to Figure 1 showing the resetting position of the switch blades.

Figures 5 and 6 are vertical sectional views on the lines 5—5 and 6—6 respectively of Figure 1, and

Figure 7 is an enlarged sectional view on the line 7—7 of Figure 1.

On the accompanying drawings I have used the reference numeral 10 to indicate a switch blade and 12 an actuating blade. The switch blade 10 carries a movable contact 14 for engagement with a stationary contact 16. The contact 14 is car-

ried by a supporting blade 18 which is somewhat resilient to prevent bouncing of the contacts when they close as disclosed in the copending application of Leland B. Wagner, Serial No. 514,483, filed December 16, 1943, which application has become abandoned.

My warp switch further includes a toggle spring 20 having its ends mounted on projections 22 and 24 of the switch blade 10 and the actuating blade 12 respectively (see Fig. 5). The switch blade has an opening 26 cut therein for the purpose of permitting clearance for the spring 20.

A bimetal element 28 of blade-like character is also provided having its upper end bent as at 30. A pair of heater supporting clips 32 are provided, to the ends of which an electric heater 34 (formed of a coil of resistance wire) are connected. The central portion of the coil is wrapped around the projection 30 of the element 28 with the heater coil under tension to prevent it from sagging when heated.

A reset button 36 is provided having a shank 38 slidable through a supporting blade 40 and an ear 42 thereof. The reset button is biased toward the left in Figure 1 by a spring 44 interposed between the ear 42 and a cotter pin 46 through the shank 38. The shank 38 has a reduced end 48 fitting loosely through an opening 50 in the switch blade 10 and adapted to coact with the contact blade 18 during resetting operations, as shown in Figure 4.

I provide another supporting blade 52 having adjusting screws 54 for coaction with the actuating blade 12 as shown in Figure 3, and a U-shaped clip 56 (see Fig. 7) which is adapted to adjust the position of the switch blade as in Figure 4 by contact therewith. The clip 56 is held away from the blade 12 by a leaf spring 58 and may be adjusted toward it by an adjusting screw 60 where by the ears of the clip may be adjusted relative to the rigid blade 52.

The switch blade 10, the actuating blade 12, the supporting blade 18, the bimetal element 28, the heater supporting clips 32, the supporting blade 40 and the supporting blade 52 are all supported in a stack of insulation spacers 62 with the exception of the blades 10 and 12 which are next to each other. The various blades to which circuit connections are made are provided with terminal ears 64 to which circuit wires may be soldered.

The stack of blades and insulation spacers are clamped between brackets 66 and 68 by a pair of screws 70, the screws extending rotatably through the bracket 66, through insulation sleeves 72 in the

holes of the blades and spacers, and threaded into the bracket 68.

Practical operation

In the operation of my warp switch, when it is set as in Figure 1, current flows across the contacts 14 and 16. When current of sufficient magnitude flows through the heater 34, it will be heated and warp the bimetal element to the position shown in Figure 3 which causes the toggle spring to snap to the opposite position for separating the contacts. The position of the toggle spring is determined by adjustment of the screw 54 whereby the characteristic of the "snap-to-open" position may be changed as desired.

After the heater 34 has cooled, the switch may be reset as in Figure 4 by pushing on the button 36 which changes the position of the toggle spring and causes the switch to snap toward closed position. As long as the button 36 is held in, the reduced portion 48 thereof holds the supporting blade 18 in such a position that the contacts are disengaged thereby and provide "trip-free" operation thus preventing the holding of the contacts closed when the bimetal element 28 is still warped to a position requiring the contacts to be open. The resetting position of the switch blade 10 may be adjusted by means of the screw 60 so that the spacing of the contacts from each other while the reset button is held in, may be varied as desired.

A warp switch of the character disclosed has its most general application as a safety switch in connection with oil and gas burner systems. When a burner operation is initiated there may be an initial failure of combustion or a failure of combustion subsequent to successful establishment thereof. If combustion is successfully established within the timing period of the heater, the heater is deenergized and therefore the warp switch does not trip. On the other hand, if there is initial or subsequent failure, this results in energization of the heater long enough so as to operate the warp switch to the position of Figure 3.

From the foregoing specification it will be obvious that I have provided a warp switch, the elements of which are inexpensively fabricated and assembled together with the insulation spacers 62 between the brackets 66 and 68 to form the complete switch. The assembling operations are not at all complicated and after the parts are assembled the switch may be tested and readily adjusted for proper operation by the two screws 54 and 60.

Some changes may be made in the construction and arrangement in the parts of my warp switch within the scope of the appended claims without departing from the real spirit and purpose of my invention. I therefore intend to cover by my claims such modified forms of structure or use of mechanical equivalents as may be reasonably included within their scope.

What I claim as new and desire to secure by Letters Patent of the United States is:

1. In a warp switch, a switch blade, a movable contact carried thereby, a stationary contact for coaction with said movable contact, an actuating blade, a toggle spring connection between said actuating blade and said switch blade, a bimetal element, a heater therefor, and heater supporting clips for said heater, said bimetal element coacting with said actuating blade to actuate the same and thereby operate said switch blade through said toggle spring, said blades, said bimetal element and said clips being supported in a stack of insulation spacers, and said heater having its ends connected to said clips and its center portion connected with and supported by said bimetal element.
2. In a warp switch, a switch blade, a movable contact carried thereby, a stationary contact for coaction therewith, an actuating blade, a toggle spring connection between said actuating blade and said switch blade, a bimetal element, a heater therefor, supporting clips for said heater, said heater being supported by said bimetal element and said supporting clips, said bimetal element coacting with said actuating blade to actuate the same and thereby operate said switch blade through said toggle spring, said blades, said bimetal element and said supporting clips for said heater being supported in a stack of insulation spacers, and means for resetting said warp switch.
